UNITED STATES PATENT OFFICE.

ALVIN H. SHOEMAKER, OF OAKLAND, CALIFORNIA.

ROTARY ENGINE.

1,379,653.

Specification of Letters Patent. Patented May 31, 1921.

Application filed June 13, 1917, Serial No. 174,768. Renewed September 7, 1920. Serial No. 408,771.

To all whom it may concern:

Be it known that I, ALVIN H. SHOEMAKER, citizen of the United States, residing at Oakland, in the county of Alameda and State of California, have invented certain new and useful Improvements in Rotary Engines, of which the following is a specification.

This invention relates to rotary engines of a type wherein the rotating elements are inclosed within a casing and are provided with intermeshing abutments and the axes of the said elements are disposed at an angle to each other.

The principal object of the present invention is to provide a device of this character in which continuous rotating motion is obtained by utilizing the expansive power of a suitable gaseous medium.

Another object of the present invention is to so arrange the various parts that they may be easily constructed and effectively lubricated by a simple force feeding system, and a still further object of the invention is to provide an engine that may be readily adapted either to the use of steam or a high pressure gas.

With these and other objects in view, the invention consists of certain novel features of construction, combinations and arrangements of parts hereinafter described and more specifically pointed out in the appended claims; it being understood that changes in form, proportion, size and minor details of construction within the scope of the claims may be resorted to without departing from the spirit of the invention or sacrificing any of the advantages thereof.

Referring to the drawings forming a part of this specification,

Figure 1— is a view in elevation of my improved rotary engine with certain portions thereof broken away to disclose the interior structure.

Fig. 2— is a vertical transverse section of the same.

Fig. 3— is a fragmentary view in side elevation of the rotating disks showing how they intermesh.

Fig. 4— is a view in section of a modified form of my engine whereby a greater degree of expansion is secured.

Fig. 5— is a view in side elevation of the rotating members used in connection with the modified form shown in Fig. 4.

Fig. 6— is a fragmentary view in end elevation of my improved engine showing a portion of the combustion chamber in section and the manner of maintaining continuous combustion therein.

Referring to corresponding parts in the several views by the same numerals of reference, my engine consists of a casing formed in two parts denoted by 2 and 3. As here shown, these members are substantially symmetrical with respect to each other and consist of the flat plates 4 with the annularly disposed rims 6, the outer edges of which are provided with flanges 8 by which the two parts are bolted together. Each portion of the casing is provided with the centrally disposed axial hub 10 in which are provided bearings 12 and 13.

The adjoining surfaces of the flanges 8 are angularly disposed with reference to the plane of the plates 4, consequently the axes 75 of the hubs 10 are disposed at an angle to each other. The apex of the angle formed by the axes of hubs 10 is in the plane which passes through the adjoining faces of the flanges 8. Designating this point by 0, it 80 will be noted that the inner surface of the rims 6 is that of a sphere having the point 0 for its center.

Journalized in bearing 13 of member 2 is a shaft 16 which extends into the casing and 85 has keyed thereon a disk 17, the hub 15 of which is journaled in bearing 12. This disk at the center, is provided with a substantially semi-spherical boss 18 which has the point 0 for its center and which is adapted 90 to coöperate with the spherical recess 19 formed in the surface of the disk 20 that is similar to disk 17. Disk 20 has a hub 21 and is keyed to a shaft 21 which in turn is journaled in bearing 13 of member 3, while the 95 hub 22 is journaled in bearing 12 of the same member.

The faces of disks 17 and 20 are conical in contour and if these faces were extended would have their apex at the point 0. They 100 are provided with a number of similarly shaped symmetrically disposed coöperating teeth 24, which are so constructed that the outer point A of each tooth of one disk constantly bears against the rear surface of the preceding tooth of the other disk during a half revolution of the disks. The outer peripheral surfaces of disks 17 and 20, as well

as the outer ends of teeth 24 are finished to a spherical surface having the same radius as that of the inner surface of the rims 6.

At their outer edges the rear surfaces of 5 disks 17 and 20 are in contact with the inner surfaces of plates 4 and are provided at this point with oil grooves 26. These grooves are in communication through a passageway 27 with a pipe 28, leading to a source of oil 10 supply which is under pressure. Likewise shaft 20 is provided with an axial opening 29 which is connected through the gland 30 to a pipe 31 leading to a supply of oil under pressure.

15 At the point of the casing where the side plates of members 2 and 3 are nearest to each other, there is provided an inlet passageway 32 which is a continuation of a cylindrical combustion chamber or a gaseous 20 intake chamber 33. As here shown, the upper and lower surface of the intake 32 are tangential to the periphery of the rotating elements and diverge from the width of the combustion chamber 33 to the width between 25 the opposite faces of the disks 17 and 20. At a point substantially diametrically opposite this intake opening, there is provided an exhaust passageway 34 which extends around the casing to a point adjacent the intake 30 opening.

In the modified form shown in Fig. 4 the casing 1 has its side surfaces separated by a greater angle while the conical surfaces of disks 17' and 20' are on a more acute angle. 35 These disks have each a spherical recess in which is loosely seated the ball 40 which in turn is provided with radial blades 41. The width of these blades is equal to the height of teeth 24' which correspond to 40 teeth 24.

As shown in Fig. 5, the rear surface of teeth 24' is of such a curve that the point B of the blades 41 is in constant contact therewith throughout the length of the 45 blade from the time it passes the intake port until it reaches the exhaust passageway. In like manner, the rear surface of the blades are curved to contact with the point C of the following tooth under the same 50 conditions.

One of the shafts which carries disk 20' or 17' is provided with an oil groove 29' connected the same as previously described, to a source of oil under pressure. The ball 55 40 has an axial passageway 42 the ends of which are enlarged as at 43, that it may always be in communication with the passageway 29' through the varying positions which the ball assumes with respect to the disks. 60 Thus oil which is forced into passageway 29' finds an outlet between the surface of ball 40 and the recesses in disks 17' and 20'. This oil then travels outwardly and lubricates the contacting surfaces of the teeth 65 and blades.

In this modified form it will be apparent, that the ratio of least and greatest opening between disks is as one to three whereas in the main form described, this ratio is as one to two. It will also be noted that I have 70 shown the teeth 24' as being cut away on the non-contacting side and by this means it is possible to govern the amount of expansion within the cavity formed by adjacent blades. Thus, the more the teeth are 75 cut away, the less will be the expansion ratio or increase of volume between adjacent teeth when at the top and when at the bottom of the casing.

I have shown in Fig. 6 a modification of 80 this engine whereby it is adapted for the use of hydrocarbon fuels directly, this being accomplished by providing three storage reservoirs as 50, 51 and 52, for water, liquid fuel and air respectively. The air is maintained under high compression of any suitable means which it is not deemed necessary here to show and is connected to the top of the fuel and water tank through suitable pipes in which are provided check valves 53 85 90 so that the contents of tank 50 and 51 cannot flow back into the air tank.

Attached to the intake 33 is a combustion chamber 54 having at the rear a plug 55 through which extends two electric conductors 56 between the points of which is held a suitable high resistance conductor 61 that is adapted to be heated to incandescence by means of an electric current.

Tubular connections 57 and 58 are provided from the air and fuel tank respectively, to the combustion chamber, these connections passing through the walls of the combustion chamber at diametrically opposite points.

105 It will be noted that the pipe 57 is of larger diameter than pipe 58 which latter extends a short distance inside the former. In like manner, a connecting pipe 59 is provided from the water tank and extends 110 through the walls of the combustion chamber and terminates in an L-shaped continuation therein, this portion having its exit opening directed away from the air and fuel inlet pipes. Each of these connecting pipes 115 is provided with a regulating valve 60 whereby the amount of each of these elements may be separately controlled.

The operation is as follows: When gas under pressure is admitted to the intake orifice 120 32 it strikes against the edges of the teeth 24 and flows downwardly into the spaces there-between. To this extent the device acts as an impact motor but as soon as the 125 inclosed space between the teeth passes the tangent point 62, a closed chamber is formed in which expansion of the gas takes place. This expansion tends to cause that part of the disks to travel apart and as the disks are axially inclined, there is a turning move- 130

ment which causes the disks to rotate to the position where there is greatest distance between the faces of the opposite disks at that point or as here shown, to the bottom of the 5 casing.

When this point is reached the cavity between the teeth is placed in communication with the exhaust passageway whereby the steam or other expansible gas is exhausted.

10 If one of the shafts, say 16, is connected to the driven mechanism and the other turns free, then during the time the disk travels from the intake port to the exhaust outlet, the forward point of the teeth on the free 15 disk, throughout the entire length of the tooth, is in contact with the rear surface of the preceding teeth of the other disk, but as the lowermost position is passed, an opposite condition takes place, but as during the 20 next half revolution, the cavities between the teeth are in constant communication with the passageway 34, no compression is possible between the adjacent teeth.

In operating the engine with the modified 25 form shown in Fig. 6, the fuel and air valves are first opened causing a combustible mixture to flow into chamber 54. This mixture is ignited by the hot wire 61 and when once ignited, continues to burn as long as the 30 fuel and air supply is maintained. The combustion thus produced takes place under pressure which is governed by the load on the engine and may be anything up to the pressure within the air tank 52. After the 35 combustion has heated things up, the valve to the water supply is opened and a stream of water sprayed into the combustion chamber. This water is immediately converted into steam the expansive power of which is 40 utilized in the engine and which at the same time serves to cool the combustion chamber.

I claim as new and wish to cover by Letters Patent:

1. A motor of the type described comprising a casing, a pair of revoluble disks mounted in said casing, said disks having angularly disposed axes, intermeshing continuously contacting abutments on the faces of said disks inclosing expansion cavities, 50 and said casing having an intake orifice and a discharge passage for communicating with said cavities.

2. A motor of the type described comprising a casing, angularly disposed end plates 55 on said casing, a pair of disks revolubly mounted in said casing and having their axes at right angles to said end plates, intermeshing abutments on the faces of said disks inclosing expansion cavities and said 60 casing having an intake orifice and a discharge passage adjacent the points where said side plates are respectively at their nearest and farthest distance apart.

3. A motor of the type described comprising a casing, angularly disposed end

plates on said casing, disks having conical adjacent surfaces revolubly mounted in said casing, a spherical lug formed on one of said disks adapted to seat in a spherical recess formed in the other of said disks, intermeshing abutments formed on the faces of said disks and extending from said lug and said recess to the inner peripheral surface of said casing forming expansion cavities, and said casing having an inlet opening and an 75 exhaust opening adjacent the points where said expansion cavities have respectively their least and greatest volumes.

4. A motor of the type described comprising a casing, rotating elements mounted in said casing with their axes angularly disposed with reference to each other, intermeshing continuously contacting abutments on said rotating elements forming chambers of varying volume as said elements revolve, 80 and means for admitting an expansible fluid into said chamber at the point of least volume, and said casing having an exhaust outlet adapted to communicate with said chambers where they have their greatest 85 volume.

5. A motor of the type described, a pair of conical faced revoluble disks having angularly disposed axes and having their apexes meeting on the point of intersection of said axes, a casing inclosing said disks and having an intake opening and an exhaust passageway, and intermeshing abutments which remain in continuous contact formed on the faces of said disks said 95 abutments forming closed cavities which increase in volume from said intake opening to said exhaust opening.

6. A motor of the type described comprising a pair of revoluble disks having angularly disposed intersecting axes, a casing surrounding said disks and having intake and exhaust passages, and abutments formed on said disks which are in constant contact with one another and form closed cavities 100 which increase in volume from said intake passage to said exhaust passage.

7. A motor of the type described, a pair of conical faced revoluble disks having angularly disposed axes and having their 115 apexes meeting in the point of intersection of said axes, intermeshing abutments integrally formed on the faces of said disks, curved faces of said abutments which remain in contact at all points in the revolutions of said disks, a casing inclosing said disks, an intake opening, and an exhaust passageway communicating with said cavities at their points of least and greatest 120 expansion.

8. A motor of the character described, a casing, disks revolubly mounted therein so that their faces have a point of maximum and a point of minimum approach, intermeshing abutments extending outwardly 125 130

from the faces of said disks a distance greater than the difference between the maximum and minimum approach of said disks, an intake orifice adjacent said point of minimum approach and an outlet orifice extending from said point of maximum approach.

9. A motor of the character described, a casing, disks revolubly mounted therein so 10 that their opposed faces have points of

maximum and minimum approach, intermeshing abutments having continuously contacting faces extending out from said faces a distance greater than the difference between the maximum and minimum approach of said disks and said casing having intake and outlet openings adjacent said minimum and maximum points respectively. 15

In testimony whereof I affix my signature.

ALVIN H. SHOEMAKER.
